UNITED STATES PATENT OFFICE.

OTTO SCHMIDT, OF HASPE, GERMANY.

FLAME-EXTINGUISHER.

1,031,203.

Specification of Letters Patent.

Patented July 2, 1912.

Original application filed March 9, 1911, Serial No. 613,420. Divided and this application filed October 3, 1911. Serial No. 652,644.

To all whom it may concern:

Be it known that I, Otto SCHMIDT, a subject of the King of Prussia, of 4 Kurze-strasse, Haspe, in Westphalia, in the Kingdom of Prussia, Empire of Germany, master coppersmith, have invented certain new and useful Improvements in Flame-Extinguishers; and I do hereby declare the following to be a full, clear, and exact description of the invention, such as will enable others skilled in the art to which it appertains to make and use the same.

My present invention relates to flame-extinguishers and more particularly to that kind thereof especially adapted to be used in connection with the filling, storing and tapping-off of igniferous liquids, such as benzine, coal-oil and the like.

The object of my invention is to produce a flame-extinguisher of the above-named kind, which in case of conflagration will prevent the flames from entering the storage-tank, transport-barrel or other receptacle employed for the reception of igniferous liquids. To obtain this end I provide a tubular body, easily and conveniently attachable to the receptacle and penetrating into the latter to a convenient depth, with a series of longitudinal slots arranged above its solid bottom and cover them by a bell-shaped hood in such a manner, that any gaseous or liquid matter which passes said series of slots and enters said hood shall be deflected toward the mouth of the latter and thus be compelled to pass a second series of narrow slots, which cross the annular-shaped mouth of said hood in a radial direction. By these means I compel any flame which by chance and under extraordinary favorable conditions, may pass the first series of slots to become extinguished before it can reach the second series of slots, since before reaching the latter it will be cooled-off below the burning-temperature through the combined action of passing the first set of slots and changing its direction.

This application is a division of an application filed by me on March 9th, 1911, under Serial number 613,420.

50 In the accompanying drawing:—Figure 1

is a vertical sectional view of an apparatus for unexplosively storing and drawing-off igniferous liquids, equipped with flame-extinguishers according to my present invention. Fig. 2 is a longitudinal-sectional view 55 of my flame-extinguisher on a larger scale. Fig. 3 is a cross-sectional view of the flame-extinguisher taken on line A—B of Fig. 2.

The apparatus in connection with which my flame-extinguisher is shown broadly 60 consists of the storage-tank 1, the overflow-chamber 2 seated upon said storage-tank, and a casting 3 which is secured to said overflow-chamber and carries the stand-pipe 4 upward through the roof of the building, 65 whereas a short pipe 5, which extends downward within a short distance above the bottom of the overflow-chamber 2 is secured between the latter and the casting 3 by means of its annular flange. Within the casting 3 70 and the stand-pipe 4 the discharge column 6 is arranged, which within the casting 3 is enlarged to form a double-seated valve-casing 7 to which is attached the feed-pipe 8 connected with a feed-barrel (not shown). 75 The latter is usually likewise provided with a flame-extinguisher to prevent explosions either when filled or emptied. To the lower part of the valve-casing 7 the tubular body 9 of my flame-extinguisher is attached through 80 which the guide-rod 10 of the swimmer 11 passes, which through contact with the tappets 12 and 13 of said rod alternately opens and closes the valves 14 and 15 likewise seated upon said rod. The latter is balanced by the weighted lever 16 which is always returned to its normal position by the aid of its weighted arm 17, as clearly shown in Fig. 1. Through the bottom of the overflow-chamber also passes the outlet-pipe 18 which carries a second flame-extinguisher. The tubular-body 9 of the latter passes through said outlet-pipe upward and is screwed into the top of the overflow-chamber 2. 95

The flame-extinguisher itself consists of a tubular body 9 provided with a solid bottom 9' over which a series of very narrow slots 19 is longitudinally arranged, which of course might be arranged differently or re- 100

placed by a series of other fine perforations. These slots or perforations are covered by a bell-shaped hood 20 of such a diameter that an annular space 21 is formed which is 5 closed up by a false bottom 22 secured to said solid bottom 9' by means of the screw 23. To give any gaseous or liquid matter which may pass through the slots 19 a free 10 exit the annular part of the false bottom bounding said annular space in the downward direction is provided with a series of narrow perforations or slots 24, running 15 preferably in a radial direction as indicated in Fig. 3. Minor details may of course vary from case to case without affecting the efficiency of the flame-extinguisher. A comparison of the two flame-extinguishers I and II shown in Fig. 1 will verify this.

The operation of the flame-extinguisher 20 is as follows:—Supposing igniferous liquid is fed through the feed-pipe 8 into the valve-casing 7 and passes in succession through the slots 19 and 24, to enter the storage-tank 1 and displace the pressure- 25 water 25 therefrom by pressing it through the flame-extinguisher II which dips into said pressure-water; then the latter leaves the storage-tank through the tubular-body of the last-named flame-extinguisher and 30 is carried off by means of the elbow 26 and the pipe 27 connected therewith, since it finds the least resistance in this direction. During the inflow of the igniferous liquid the swimmer 11 is gradually lowered until 35 it strikes the tappet 13 whereupon the valve 15 will be closed and the valve 14 opened to its fullest extent. If now during the emptying of the storage-tank 1 in case of a fire the igniferous liquid contained in the discharge- 40 pipe 6 in spite of the cooling-water admitted through the pipes 4 and 28 should get heated to such an extent that an explosion at the overheated spot is unavoidable, one part of the flames and powerful gases 45 formed thereby would find an exit through the safety-valve (not shown) closing the discharge-column 6, whereas the other part thereof would pass downward to the storage-tank 1. Since the feed-pipe 8 is closed 50 by a check-valve 29, the flame will force its way downward through the tubular body 9 of the flame-extinguisher I and try to find its way through the series of slots 19, which of course can be accomplished under the 55 most favorable conditions only. Even granted that this should take place the flame would get cooled-off thereby to such an extent that in combination with the loss of heat sustained through the change of direction toward the second series of slots 24 it would be completely extinguished and the 60 remaining gaseous matter reduced to such a low temperature that after passing the second series of slots it would be incapable

of igniting the igniferous liquid contained 65 in said storage-tank. Hence an explosion of the liquid through the instrumentality of a flame entering by way of the valve-casing 7 is fully excluded.

In case a fire should break out near the 70 storage-tank 1 itself and heat it to such an extent as to form gases of a considerable pressure, they would escape through the flame-extinguisher I arranged within the neck of said tank and thus pass off through 75 the discharge-column 6. A rising of the temperature of the contents of said storage-tank to such an extent that an explosion can take place therein is impossible, since to accomplish this, the whole body of igniferous 80 liquid would have to be raised to the ignition-point which of course would take a sufficiently long time to have the fire quenched, besides which the means employed for automatically preventing such 85 an increase of the temperature of the liquid would have been set into action in the manner fully described in my application of March 9, 1911. Should, however, through 90 a combination of extraordinary and untoward circumstances the pipe 27 be destroyed so that a flame might pass through the tubular body 9 of the flame-extinguisher II it would be extinguished in the same manner as explained above in connection 95 with the flame-extinguisher I, if not extinguished before by passing through the pressure-water 25, so that from this direction too an explosion of the igniferous liquid stored in the tank 1 is excluded.

The flame-extinguishers will of course act in the same safe manner when on filling or emptying the storage-tank 1 the igniferous liquid should get ignited through carelessness of the laborers, since in any of these 105 cases the flame would have to pass again through the flame-extinguisher I, which as shown above, is impossible.

I claim:—

1. A flame-extinguisher for preventing 110 explosions of stored igniferous liquids, consisting of a tubular body provided with a series of narrow slots, a solid bottom limiting said slots in one direction, a hood surrounding said series of slots to leave between said hood and said series of slots a free space, and a false bottom provided with a series of slots communicating with said free space and arranged at right angles to the first-named series of slots.

2. A flame-extinguisher for preventing 115 explosions of stored igniferous liquids, consisting of a tubular body provided with a series of narrow longitudinal slots and adapted to be inserted into the liquid-receptacle, a solid bottom closing one end of said tubular body and simultaneously limiting said slots in this direction, a bell-shaped 120

hood surrounding said series of slots to
form a free annular space between said hood
and said series of slots, and a false bottom
provided with a series of radial slots com-
5 municating with said annular space and ar-
ranged at right angles to the first named
series of slots.

Signed by me at Barmen, Germany, this
14th day of September 1911.

OTTO SCHMIDT. [L.S.]
